A. MEISSNER

ARC TRANSMITTER FOR WIRELESS TELEGRAPHY

Filed Sept. 3, 1921

Inventor
ALEXANDER MEISSNER

By his Attorney

Dr. J. Adams

UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

ARC TRANSMITTER FOR WIRELESS TELEGRAPHY.

Application filed September 3, 1921. Serial No. 498,416.

(GRANTED UNDER THE PROVISIONS OF THE ACT OF MARCH 3, 1921, 41 STAT. L., 1313.)

To all whom it may concern:

Be it known that I, ALEXANDER MEISSNER, citizen of the German Republic, residing at Berlin, Germany, have invented certain new and useful Improvements in Arc Transmitters for Wireless Telegraphy (for which I have filed applications as follows: Germany, Patent No. 297,965, filed July 3, 1914; Great Britain, Patent No. 19,331), of which the following is a specification.

It is well known that in the use of arc lamp transmitters on board merchant ships, two kinds of difficulties are encountered; first, it is impossible to produce the short, internationally permitted waves of 300 to 600 meters, because when the short wave length is established, the disadvantage is observed that the period varies materially; such senders operate satisfactorily only with greater wave lengths from 2000 meters, up.

A further drawback consists in that the sending signals for which undamped oscillations are used, can be received only by special receiving devices, with the result that each ship that carries a spark sender, must also be provided with special devices in its sender to enable the reception of messages from stations equipped with arc lamp senders.

The present invention avoids all these difficulties. The invention consists in the use with an arc lamp of frequency increasing arrangements, which, for example, may be like those heretofore used with high frequency machines, irrespective of whether the increased frequency is an even or odd multiple. Obviously, only those frequency increasing means can come into consideration which operate with magnetically saturated iron, i. e., arrangements such as are described in German Patent, No. 149,761, for doubling the period, or multiplying arrangements of the type described in German Patent, No. 264,250. In this manner, the international wave length of 600 meters may be produced by generating waves of 1200 to 1800 meters by means of an arc, and doubling or tripling the frequency of these waves by means of static frequency changers.

Together with the multiplying of the frequency, we may affect also the energy sent

out in a very simple manner, whereby the signals will be audible in an ordinary receiver that is constructed for the receiving of spark signals. This is accomplished by varying the auxiliary magnetizing of the frequency changer in accordance with sound signals, e. g., by providing in addition to the two alternating current windings and the normal direct current winding, a fourth winding through which is conducted alternating current or cut up direct current corresponding to a tone frequency. From this results a further advantage consisting in that the operation of the key to interrupt or vary this auxiliary alternating current may be eliminated, whereby the arc lamp will not be disturbed and will continuously operate during signaling.

Finally, by means of such arrangement wireless telephony may be easily effected. All that is necessary is to send instead of alternating currents, microphone currents through the fourth winding of the period transformer.

My invention is illustrated by the single figure of the accompanying drawing. *a* is an arc lamp generator having a source *A* of direct current, and *b* and *c* are two transformers of the frequency changer. The primary windings *d*, *e*, of both transformers are connected in the circuit of the generator, *a*, condenser *f* serving for tuning. The secondary windings *g*, *h*, of the transformers are connected with the antenna *i*. A second frequency increasing device might be provided and serve for delivering the current to the antenna. The auxiliary direct current magnetizing windings *k*, *l*, are supplied in the well known manner, from a constant direct current source *m*. The sound frequency may be produced, e. g., by both windings *n*, *o*, which may be fed by an alternating current of suitable frequency, or their circuit may comprise also a microphone for the transmission of speech.

Claims:

1. An arc transmitter for wireless telegraphy and telephony comprising an antenna, an arc generator, and means interposed between the generator and the antenna for producing an even or odd multiple of the frequency of the oscillations

produced by the generator without damping said oscillations, said means including a frequency changer having saturated iron cores.

5. 2. In an arc transmitter for wireless telegraphy and telephony, an arc generator including a pair of electrodes and a source of direct current connected to the electrodes, a pair of saturated iron cores, primary windings on said cores, an oscillating circuit including said windings and the arc electrodes, a condenser in said circuit for tuning the circuit to the fundamental fre-

quency of the generator and for preventing the passage of direct current from said direct current source to the iron cores, an antenna, secondary windings on said cores connected with the antenna, direct current windings for effecting auxiliary magnetization of said cores, and means for influencing the energy in the secondary windings in accordance with signals to be transmitted.

In testimony whereof I affix my signature,

ALEXANDER MEISNER
